UNITED STATES PATENT OFFICE.

PERCY I. ANSORGE, OF BROOKLYN, NEW YORK.

DESIGN FOR A LIGHTING-FIXTURE PART.

47,316.

Specification for Design.

Patented May 11, 1915.

Application filed March 8, 1915. Serial No. 12,981. Term of patent 3½ years.

To all whom it may concern:

Be it known that I, PERCY I. ANSORGE, a citizen of the United States, residing at 1342 Forty-ninth street, borough of Brooklyn, county of Kings, and State of New York, have invented a new, original, and ornamental Design for Lighting-Fixture Parts, of which the following is a specification, reference being had to the accompanying drawing, forming part thereof.

Figure 1 is a bottom plan view, and Fig. 2 a side elevation, showing my new design for a lighting fixture part.

I claim:

The ornamental design for a lighting fixture part, as shown.

PERCY I. ANSORGE.
